COMPOSITIONS CONTAINING N-ALKYL-BETA-AMINO PROPIONATES AND GERMICIDAL QUATERNARY AMMONIUM COMPOUNDS

Royce G. Freese, Minneapolis, Minn., assignor to General Mills, Inc., a corporation of Delaware
No Drawing. Filed May 3, 1957, Ser. No. 656,773
3 Claims. (Cl. 252—106)

This invention relates to new and useful compositions containing an amphoteric anionic-form detergent and a cationic quaternary compound.

Heretofore, it has been the practice to mix quaternary compounds with either non-ionic or cationic surface active agents due to the fact that they were incompatible with anionic acting detergents. The usual result accompanying the mixing of a quaternary compound and an anionic acting detergent is the formation of an insoluble precipitate.

It has now been discovered that various germicidally active quaternary compounds form a compatible and stable mixture with amphoteric anionic-form detergents of the general structural formulas $RHNCH_2CH_2COO^-$ and $RN(CH_2CH_2COO^-)_2$ where R is an aliphatic hydrocarbon radical containing 8 to 22 carbon atoms, and X is a salt-forming radical, hereinafter referred to as the "mono- and di-propionate adducts" of the various fatty amines RNH_2 .

It is therefore, the primary object of this invention to disclose compositions that contain quaternary compounds and amphoteric anionic-form surface active agents which form a compatible and stable mixture and which retain and enhance their useful properties in various applications. For instance, the germicidal activity of the quaternary compounds are unimpaired as are the surface activity characteristics of the amphoteric anionic-form detergent. These compositions are especially useful in shampoos, sanitizers, textile treating agents, clothes softening compositions, liquid dishwashing compositions, and the like.

Various quaternary compounds may be employed in the practice of this invention. They may be represented structurally by the following formula $R^1R^2R^3R^4NY$ where R^1 , R^2 , R^3 , and R^4 are hydrocarbyl radicals and Y is an inorganic anion such as chloride, sulfate, bromide, and related radicals. A commercially important class of quaternary compounds is where R^1 and R^2 are lower alkyl radicals containing 1 to 4 carbon atoms, R^3 is an aralkyl radical, and R^4 is an aliphatic hydrocarbon group containing 8 to 22 carbon atoms. One readily available and effective member of this class is lauryl dimethyl benzyl ammonium chloride. Another useful class of quaternary compounds are those in which R^1 and R^2 are lower alkyl radicals containing 1 to 4 carbon atoms, and R^3 and R^4 are aliphatic hydrocarbon radicals from fatty acids containing 8 to 22 carbon atoms. An effective member of this is dicoco dimethyl ammonium chloride, where "coco" represents the fact that these aliphatic hydrocarbon radicals were derived from the fatty acids of coconut oil.

2

The salt-forming group of the amphoteric anionic-form surface active agent, i.e., the mono- and di-propionate adducts will generally be their alkali metal salts, preferably sodium or potassium, due to their ease of preparation and the economics of the situation. However, for certain specialty applications it may be preferable to use an organic salt. In these instances the salts of triethanol amine have been found to be useful. In any case it will be appreciated that the anionic surface activity of these salts are due to the presence of the radicals

and

It is also noted that this type of surface active agent only foams and exhibits its known desirable detergent characteristics when it is present in its anionic form.

It will also be appreciated that the unique combination of an amphoteric anionic-form detergent and cationic quaternary compounds taught by this invention may be admixed with other substances commonly utilized in the applications to which it is to be employed. Obviously, it will generally be employed in the form of a water solution. Other common ingredients which may be admixed with the compositions of this invention are non-ionic surface active agents, humectants such as glycol, lower alcohols, preferably ethyl alcohol, and phosphates. In the preparation of the various solutions contemplated by this invention, the amphoteric anionic-form detergent either mono- or di-adduct must be present on a weight basis at least in the ratio of 1 to 1 to the amount of quaternary compound in order to obtain water solutions containing at least 10% solids by weight. Concentrated solutions of this type may be merchandised as shampoos and other liquid detergent compositions and the stability and compatibility of the ingredients are retained at the lower concentrations employed in the actual utilization of the compositions. Depending on the application for which the compositions are to be employed, the ratio of ingredients may vary from the above ratio which is the lower limit for purposes of compatibility. For instance, as much as 15 parts of the amphoteric anionic-form detergent may be employed in admixture with 1 part of the germicidal quaternary compounds.

This invention may be illustrated further by reference to the following examples in which all "parts" are expressed as parts by weight and all "percentages" are expressed as percent by weight, unless specified otherwise.

EXAMPLE I

50 Test solutions were prepared of lauryl dimethyl benzyl ammonium chloride and coco beta-aminopropionate (the compound derived from the mixed amines of coconut oil acids). These test solutions were combined in various proportions as indicated in the following table and were 55 tested at different levels for their germicidal properties on *E. coli* and *S. aureus*. The results are indicated in the following table.

Test solution, percent	Active conc. in p.p.m.		<i>E. coli</i>		<i>S. aureus</i>	
	On basis of detergent and sanitizer	On basis of sanitizer	30 sec. expos.	2 min. expos.	30 sec. expos.	2 min. expos.
Lauryl dimethyl benzyl ammonium chloride	Coco beta aminopropionate					
100	0	200	200	0	0	0
		100	100	1	0	0
75	25	200	150	0	0	0
		100	75	1	0	0
50	50	200	100	0	0	0
		100	50	1	0	0
25	75	200	50	3	0	0
		100	25	40	0	*TNTC
0	100	200	0	1,200	26	TNTC
		100	0	TNTC	1,000	TNTC

*TNTC—Too numerous to count.

Solutions buffered at pH 8 with 0.1 M K_2HPO_4 . Twenty-four hour broth cultures of organisms used.

These data illustrate that the germicidal effectiveness of the quaternary ammonium compound is unimpaired by the presence of the coco beta-aminopropionate.

EXAMPLE II

A solution of 1.0% lauryl dimethyl benzyl ammonium chloride plus 6.0% coco beta-aminopropionate was prepared. The solution was perfectly clear, no precipitation occurred after an extended period. This solution was next divided into two portions and diluted to typical use concentrations in the shampoo trade.

Solution I:

1.0% coco beta-aminopropionate

0.1667% lauryl dimethyl benzyl ammonium chloride

Solution II:

0.5% coco beta-aminopropionate

0.083% lauryl dimethyl benzyl ammonium chloride

Comparable solutions containing only coco aminopropionate were also prepared.

Solution III: 1.0% coco beta-aminopropionate

Solution IV: 0.5 coco beta-aminopropionate

Solutions I and III were compared for foaming properties in the standard Ross-Miles test at original pH.

	pH	Ross-Miles foam height in mm.
Solution I	11.2	200
Solution III	11.4	205
1.0% sodium	7.0	198
Lauryl alcohol		
Sulfate		

Solutions II and IV were compared at various pH's:

Solution	pH	Ross-Miles foam height in mm.
Solution II	10.5	197
Solution IV		195
Solution II	9.5	195
Solution IV		201
Solution II	7.0	183
Solution IV		187

The combination material at 1.0% concentration (Solution I) yields a foam height equivalent to that of a lauryl alcohol sulfate which holds a dominant position in the shampoo trade.

The comparison of Solutions II and IV shows that the foaming of coco beta-aminopropionate is essentially unchanged by addition of the cationic germicide.

EXAMPLE III

To a one liter solution containing 10 gms. of stearyl dimethyl benzyl ammonium chloride was added 60 gms. of coco beta-aminopropionate. The addition of coco beta-aminopropionate did not cause any further clouding of the solution nor was any evidence of precipitation visible.

EXAMPLE IV

A typical dishwashing test was used to determine if the addition of the cationic germicide, lauryl dimethyl benzyl ammonium chloride, would effect the dishwashing properties of coco beta-aminopropionate.

Test Conditions

- Soil-plates for soil by depositing thereon 5 gms. of non-emulsified shortening and the shortening allowed to age 1 hour on the plate.
- End point—point at which half of the washing surface of the aqueous liquid was no longer covered by foam.
- Temperature—115° F.

(4) Water hardness—75 p.p.m.

(5) Volume of washing solution—5 liters.

(6) Suds on the surface of the washing solution were created by pouring a stream of water into the dishpan containing the dissolved detergent.

	Solution	Initial foam height in mm.	Number of plates washed before reaching endpoint
10			
15	1. 0.05% of a typical commercial retail liquid dishwashing product of the triethanolamine lauryl alcohol sulfate type.	225	*25
	2. 0.05% coco beta-aminopropionate.	230	26
	3. 0.05% coco beta-aminopropionate+0.01% lauryl dimethyl benzyl ammonium chloride	225	27

*Test accuracy is $\pm 2\frac{1}{2}$ plates.

It will be apparent from the above that the quaternary ammonium compound does not adversely affect the detergent properties of the beta-aminopropionate. It is thus possible to have a liquid dishwashing product with germicidal activity.

EXAMPLE V

In order to study the compatibility and stability of various mono- and di-propionate adducts of various amines and various quaternary compounds, the following solutions were prepared: (a) 2 parts dicoco dimethyl ammonium chloride and 8 parts of the sodium salt of the mono-propionate adduct of coco amine were dissolved and shown to be compatible with 90 parts of water, (b) 5 parts of the dihydrogenated tallow dimethyl ammonium chloride ("tallow" designates that the fatty acid source was tallow) and 15 parts of the sodium salt of the mono-propionate adduct of coco amine were dissolved and shown to be compatible with 80 parts of water, (c) 1 part mono-tallow trimethyl ammonium chloride and 1 part of the sodium salt of the mono-propionate adduct of coco amine were dissolved and shown to be compatible with 18 parts of water, (d) 2 parts dicoco dimethyl ammonium chloride and 30 parts of the triethanolamine salt of the mono-propionate adduct of coco amine were dissolved and shown to be compatible with 68 parts of water, (e) 1 part mono-tallow trimethyl ammonium chloride and 30 parts of the triethanolamine salt of the mono-propionate adduct of coco amine were dissolved and shown to be compatible with 18 parts of water, (f) 5 parts of the dihydrogenated tallow dimethyl ammonium chloride and 15 parts of the di-sodium salt of the di-propionate adduct of lauryl amine were dissolved and shown to be compatible with 80 parts of water, and (g) 1 part mono-tallow trimethyl ammonium chloride and 15 parts of the di-sodium salt of the di-propionate adduct of lauryl amine were dissolved and shown to be compatible with 18 parts of water.

EXAMPLE VI

Table I shows various liquid detergent sanitizer compositions which may be prepared using the teachings of this invention.

Table I

Composition	Quaternary ¹	Diadduct ²	Non-Ionic ³	TKPP ⁴	Water	Ethanol
A	10	15			10	65
B	10	15	5	10	73	2
C	9.1	11.7	5.1	9.1	64	

¹ Lauryl dimethyl benzyl ammonium chloride.

² Di-sodium salt of the di-propionate adduct of octadecyl amine.

³ Polyethylene glycol alkyl aryl ether.

⁴ Tetrapotassium pyrophosphate.

Each of the above compositions formed clear solutions and exhibited all the properties of a good sanitizer.

Many modifications and variations of the invention as hereinbefore set forth may be made without departing

from the spirit and scope thereof, and therefore only such limitations should be imposed are indicated in the appended claims.

The present application is a continuation-in-part of application Serial No. 483,170 filed January 20, 1955, now abandoned.

Now, therefore, I claim:

1. A compatible and stable composition which comprises an amphoteric anionic-form surface active agent selected from the group consisting of $RHNCH_2CH_2COOX$ and $RN(CH_2CH_2COOX)_2$ where R is an aliphatic hydrocarbon radical containing 8 to 22 carbon atoms and X is a salt forming group, and a cationic germicidal quaternary compound in which said surface active agent is present at least in equal parts by weight to the amount of the quaternary compound employed.

2. A sanitizer composition comprising an amphoteric anionic-form detergent of the formula

where R is an aliphatic hydrocarbon radical containing 8 to 22 carbon atoms, the cationic germicidal quaternary lauryl dimethyl benzyl ammonium chloride, and tetrapotassium pyrophosphate in which said amphoteric anionic-form detergent is present at least in equal parts by weight to the amount of lauryl dimethyl benzyl ammonium chloride.

3. A shampoo composition which comprises a concentrated aqueous solution of an amphoteric anionic-form

detergent selected from the group consisting of

and

5 where R is an aliphatic hydrocarbon radical containing 8 to 22 carbon atoms and X is a salt forming group and a quaternary compound of the structural formula

10 where R^1 and R^2 are lower alkyl radicals containing 1 to 4 carbon atoms, R^3 is an aliphatic hydrocarbon radical containing 8 to 22 carbon atoms and derived from a fatty acid, R^4 is selected from the group consisting of benzyl and aliphatic hydrocarbon radicals containing 8 to 22 carbon atoms and derived from a fatty acid and Y is a halogen radical, in which said amphoteric anionic-form detergent is present at least in equal parts by weight to the amount of the quaternary compound employed.
